C. J. MADONNA.
HOT WATER HEATER AND STERILIZER.
APPLICATION FILED SEPT. 4, 1912.

UNITED STATES PATENT OFFICE.

CHARLES J. MADONNA, OF NEW YORK, N. Y.

HOT-WATER HEATER AND STERILIZER.

1,047,668.

Specification of Letters Patent. Patented Dec. 17, 1912.

Application filed September 4, 1912. Serial No. 718,466.

To all whom it may concern:

Be it known that I, CHARLES J. MADONNA, a citizen of the United States, and a resident of the city of New York, borough of Brooklyn, in the county of Kings and State of New York, have invented a new and improved Hot-Water Heater and Sterilizer, of which the following is a full, clear, and exact description.

10 The object of the invention is to provide a new and improved hot water heater and sterilizer, more especially designed for use in barber shops, hospitals and other places and arranged to furnish a supply of hot 15 water for shaving, and washing purposes, and at the same time permit the sterilizing of a large quantity of towels, napkins and the like. For the purpose mentioned use is made of a steam compartment, a water compartment below the said steam compartment and provided with a water inlet and a water outlet, a valved connection between the water compartment and the steam compartment to charge the latter with water from 20 25 the said water compartment, and a heating coil below the said water compartment and having its terminal in the said steam compartment.

A practical embodiment of the invention 30 is represented in the accompanying drawing forming a part of this specification, in which the figure is a sectional side elevation of the hot water heater and sterilizer, parts being in elevation.

35 On a suitably constructed stand A is mounted a boiler shell B provided in its lower portion with a water compartment C and in its upper portion with a steam compartment D, the said compartments C and D 40 being separated from each other by an outlet chamber E into which opens the upper end of a tube E' extending through the water compartment C preferably centrally therewith, as indicated in the drawing. 45 The outlet chamber E is provided in its side wall with openings E² for the escape of the products of combustion, as hereinafter more fully explained. The water compartment C is provided with a water inlet F connected 50 with a suitable source of water supply for charging the compartment C with water, and the said water compartment is also provided with a draw-off faucet G for drawing off the hot water for shaving, washing or 55 other purposes.

The steam compartment D is charged

with water from the water compartment C, and for this purpose use is made of a valved connection H connecting the water compartment C with the steam compartment D. The connection H is provided with a valve H', with a water gage H² and a draw-off faucet H³, to permit of viewing the level of the water in the steam compartment D and also to permit of withdrawing the water by the use of the faucet H³ from the steam compartment D.

Immediately below the water compartment C is arranged a heating coil I having its ends I' extending upward through the tube E' and the chamber E, the terminals I² of the ends I' being secured to the bottom of the steam compartment D and opening into the same. Below the coil I is arranged a burner J, of any approved construction, preferably, however, an oil burner connected by a fuel pipe K with a suitable source of oil supply.

On top of the steam compartment D is removably mounted a sterilizing vessel L provided with a door N and a grate O for supporting towels, napkins and other articles to be sterilized, it being understood that the grate O is preferably arranged intermediate the bottom and top of the sterilizing vessel and immediately below the bottom of the door N so that when the latter is opened the articles P can be readily placed on the grate O or removed therefrom.

When the device is in use the water from the steam compartment D passes into the coil I which latter is heated by the flame emanating from the burner J so that steam is generated and this steam passes through the water in the steam compartment D 95 through the top thereof and into the sterilizing vessel L to sterilize the articles P held in the sterilizing vessel L at the time. The water in the compartment C is also heated by the flame emanating from the burner J, 100 and the hot water can be withdrawn as needed from the compartment C by the use of the draw-off faucet G. The steam compartment D is periodically charged with water from the water compartment C by opening the valve H' so that water flows into the steam compartment D until a desired level is reached, and which level is indicated by the gage H². The products of combustion arising from the burning fuel of the burner J pass through the tube E' and into the chamber E, from which the products of com-

bustion can escape by the openings E'. It is understood that the products of combustion in passing through the tube E' heat the latter to assist heating the water contained in the water compartment C.

The combined hot water heater and sterilizer is very simple and durable in construction, can be cheaply manufactured and readily set up in a barber shop or other place to furnish hot water for shaving, washing or other purposes and to enable the barber to keep on hand a large quantity of sterilized towels, napkins and the like.

Having thus described my invention, I claim as new and desire to secure by Letters Patent:

1. A hot water heater and sterilizer, comprising a steam compartment, a water compartment below the said steam compartment and provided with a water inlet and a water outlet, a valved connection between the water compartment and the said steam compartment to charge the latter with water from the said water compartment, and a heating coil below the said water compartment and having its terminals in the said steam compartment.

2. A hot water heater and sterilizer, comprising a steam compartment, a water compartment below the said steam compartment and provided with a water inlet and a water outlet, a valved connection between the water compartment and the said steam compartment to charge the latter with water from the said water compartment, a heating coil below the said water compartment and having its terminals in the said steam compartment, a tube extending through the said water compartment, an outlet chamber intermediate the said steam compartment and

the said water compartment and into which opens the upper end of the said tube, the coil ends extending through the said tube, and a burner under the said coil.

3. A hot water heater and sterilizer, comprising a steam compartment, a water compartment below the said steam compartment and provided with a water inlet and a water outlet, a valved connection between the water compartment and the said steam compartment to charge the latter with water from the said water compartment, the said valved connection including a water gage for the steam compartment and a draw-off faucet, and a heating coil below the said water compartment and having its terminals in the said steam compartment.

4. A hot water heater and sterilizer, comprising a steam compartment, a water compartment below the said steam compartment and provided with a water inlet and a water outlet, a valved connection between the water compartment and the said steam compartment to charge the latter with water from the said water compartment, a heating coil below the said water compartment and having its terminals in the said steam compartment, and a sterilizing vessel on top of the said steam compartment and in communication therewith, the said sterilizing vessel having a door and means within the vessel for supporting the articles to be sterilized.

In testimony whereof I have signed my name to this specification in the presence of two subscribing witnesses.

CHARLES J. MADONNA.
